RAIL FASTENING DEVICE

Original Filed April 6, 1929

FIG. I.

FIG. II.

FIG. III.

FIG. IV.

INVENTOR:

RAYMOND L. VARE,

BY *John C. Lang*
Attorney

UNITED STATES PATENT OFFICE

RAYMOND L. VARE, OF GERMANTOWN, PENNSYLVANIA

RAIL-FASTENING DEVICE

Original application filed April 6, 1929, Serial No. 352,953. Divided and this application filed August 27, 1929. Serial No. 388,731.

This is a division of my application Serial No. 352,953 filed April 6, 1929, for Letters Patent of the United States for improvement in metallic railway ties. Altho my fastening device may be advantageously used with such metallic ties as described in the original application; it may also be used with other ties formed of metal or other material such as wood or concrete.

10 As hereinafter described; my invention includes a rail chair plate, which may be welded in integral relation with the upper surface of a metallic tie, or be used separately in connection with a tie formed of any material. 15 Said plate includes means for adjustably rigidly securing a rail in proper spaced relation thereon and in electrically insulated relation therewith. Such chair plates are adapted to cooperate with lever clamp blocks which are 20 respectively fulcrumed upon the outer upper edges of the ends of said plates; said plates having screw sockets extending vertically therein local to each clamp block and adapted to receive cap screws for pressing the clamp 25 blocks downwardly upon the rail flanges. Said plates also have screw sockets extending horizontally in the ends thereof adapted to receive cap screws which bear upon the outer ends of the respective clamp blocks; whereby 30 said blocks may be adjusted transversely to the rails, to properly space the latter.

My improved rail clamping means also include a locking plate whereby both of the cap screws local to each block may be prevented 35 from rotating from the position to which they are adjusted, but which may be readily released to permit said screws to be otherwise adjusted.

My invention includes the various novel 40 features of construction and arrangement hereinafter more definitely specified.

In said drawings; Fig. I is a fragmentary side elevation of a portion of a railway tie, with a chair plate and its appurtenances 45 thereon engaging a rail in adjusted position.

Fig. II is a plan view of one of the screw locking plates shown in Fig. I.

Fig. III is an end view of said locking plate.

Fig. IV is a perspective view of a modified 50 form of chair plate, having holes for screws

to connect it with a tie and having calks adapted to be imbedded in such a tie.

Referring to the form of my invention shown in Figs. I to III inclusive; the tie 1 may be formed of metal rigidly connected at its top surface with the rail chair plate 2, conveniently by spot welding. However, of course, such connection might be made by any suitable rivet or screw means. Each of said chair plates 2 has, at opposite ends thereof, similar fulcrum ribs 4. Each such plate 2 also has two screw sockets 6 extending vertically therein respectively near the opposite ends thereof, and two screw sockets 7 extending horizontally therein at the opposite ends thereof; all of said screw sockets being conveniently intermediate of the width of the plates, as indicated in Fig. IV.

I prefer to provide the screw sockets 6 with conical rims 8 at the upper ends thereof to shed water outwardly from the threads of the screws 10 which are fitted therein. Each of said chair plates 2 is provided with a pair of lever clamp blocks 12 which are fulcrumed upon said ribs 4 and adapted to be drawn downwardly by said screws 10 which extend thru slots 13 in the respective blocks. Said blocks 12 have bifurcated outer end flanges 14 adapted to receive, between their bifurcations, respective set screws 16 which extend in said screw sockets 7 in the plates 2 and are adapted to adjust said blocks 12 transversely to the base flanges 18 on the rails 20. Said blocks 12 have respective flanges 21 near their inner ends which depend in opposition to the side edges of the rail flanges 18 and determine the position of said rails.

In order to electrically insulate said rails 20 from said chair plates 2; I prefer to provide each such plate with a pad of insulating material 22. Each of said blocks 12 is also electrically insulated from the adjoining rail flange 18 by an angular pad of insulating material 24, interposed as shown in Fig. I.

In order to prevent accidental displacement of said screws 10 and 16 from any position to which they may be adjusted; I prefer to provide them with locking plates 26, each of which has an opening 27 fitted to the head of the local cap screw 10, and a notch 28 fitted

to the head of the local set screw 16; each of said plates 26 is normally in the shape shown in full lines in Figs. II and III; in which shape it may be readily fitted downwardly over the heads of both of said screws 10 and 16, as indicated in Figs. I and III. Thereupon, the prongs 30 on said locking plates 26 may be bent inwardly, as indicated in dotted lines in Fig. III, to prevent the respective locking plates from being accidentally dislodged upwardly; thus preventing rotation of both screws. However, said plates 26 are made of metal, preferably mild annealed steel, so far flexible that said prongs 30 may be rebent outwardly from the position indicated in dotted lines in Fig. III to the position shown in full lines in said figure, to permit the removal of the lock plates 26 thus released, and permit further adjustment of said screws 10 and 16, when necessary, or if it is desired to remove the local clamp block 12 or rail 20.

Referring to Fig. IV; rail chair plates 32, otherwise resembling said chair plates 2, may have a plurality of holes 33 extending therethru, for screws to engage them with ties, and have a plurality of calks 35 and 36, projecting downwardly therefrom, in transverse relation with each other, and adapted to be imbedded in the tie to which the plate is connected; so as to prevent accidental lateral displacement of such plates 32. It is to be understood that such plates 32 may be equipped with clamp blocks 12 secured by screws 10 and 16, as above described.

It may be observed that the form of my invention shown in Fig. IV is adapted for rigid connection with a wooden tie; said calks 35 and 36 being sharp at their lower edges so that they may be caused to imbed themselves in such a tie under pressure of lag screws extending thru the holes 33. Of course, other locking means may be employed in lieu of the plates 26.

Therefore, I do not desire to limit myself to the precise details of construction and arrangement herein set forth, as it is obvious that various modifications may be made therein without departing from the essential features of my invention, as defined in the appended claims.

I claim:

1. A metallic railway tie, including a top plate having chair plates integrally fixed thereon; each of said chair plates having fulcrum ribs at respectively opposite ends thereof; rail lever clamp blocks mounted on said fulcrum ribs; and screws respectively engaging said chair plates and adapted to adjust the position of said blocks toward said plates to clamp rails thereon.

2. A tie structure as in claim 1, including screws extending in said chair plates longitudinally with respect to the tie and adjustable to determine the spaced relation of said lever blocks.

3. A metallic railway tie chair plate having a fulcrum rib at one end thereof; a screw socket in said chair plate at the inner side of said fulcrum rib; and an annular rim at the top of said socket adapted to shed water outwardly from the threads thereof. 70

4. A metallic railway tie chair plate having screw sockets perpendicular to its plane respectively adjoining the opposite ends thereof; and screw sockets extending longitudinally in said plate at the opposite ends thereof, adapted to receive rail clamping screws in transverse relation to each other. 75

5. A structure as in claim 4, having fulcrum elements at respectively opposite ends thereof between said screw sockets; and lever clamp members adapted to rock on said fulcrum members, and adjustable vertically and longitudinally with respect to the tie by said screws. 80

6. Rail clamping means accessory to a railway tie, including a clamp block; adjusting screws extending in transverse relation to each other in cooperative relation with said block; and locking means for said screws, 90 including a plate having polygonal openings fitting the heads of said screws, at the opposite ends of said plate; said ends being in transverse relation to each other. 85

7. A structure as in claim 6; wherein one of the openings at the end of the locking plate is a notch having flexible prongs in bifurcated relation, adapted to be bent to detachably engage said plate and to release the same with respect to said screws. 95

8. A metallic railway tie chair plate having fulcrum members at opposite ends thereof; lever clamp blocks mounted on said fulcrum members; a pad of electrical insulating material supported by said plate intermediate of said clamp blocks; and electrical insulating members respectively engaged by the inner ends of said clamp blocks and adapted to fit the opposite edges of rail base flanges resting on said pad; and screw means connecting said blocks and plate; whereby a rail may be rigidly clamped upon said plate in electrically insulated relation therewith. 100

In testimony whereof, I have hereunto signed my name at Philadelphia, Pennsylvania, this sixteenth day of August, 1929. 115

RAYMOND L. VARE.
